US0D1105557S

(12) **United States Design Patent** (10) Patent No.: **US D1,105,557 S**
(45) Date of Patent: ** Dec. 9, 2025

(54) **LIGHTING APPARATUS WITH ELECTRICAL JUNCTION BOX**

(71) Applicant: **Patina Lighting Limited**, Dun Laoghaire (IE)

(72) Inventor: **Gerard Francis Hamilton**, Foxrock (IE)

(73) Assignee: **Patina Lighting Limited**, Dublin (IE)

(**) Term: **15 Years**

(21) Appl. No.: **29/970,521**

(22) Filed: **Oct. 29, 2024**

(30) **Foreign Application Priority Data**

Aug. 27, 2024 (GB) 6386718

(57) **CLAIM**

The ornamental design for a lighting apparatus with electrical junction box as shown and described.

DESCRIPTION

FIG. 1 is a top view of a lighting apparatus with electrical junction box;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is a perspective view thereof.

The broken lines in the drawings illustrate portions of the lighting apparatus with electrical junction box and form no part of the claimed design.
